UNITED STATES PATENT OFFICE.

LAURENT RUEL, OF ST. JOHNSBURY, VERMONT, ASSIGNOR TO HIMSELF AND JULIEN DEMERS, OF SAME PLACE.

IMPROVEMENT IN APPARATUS FOR HEATING AND ILLUMINATING.

Specification forming part of Letters Patent No. 144,414, dated November 11, 1873; application filed August 6, 1873.

To all whom it may concern:

Be it known that I, LAURENT RUEL, of St. Johnsbury, of the county of Caledonia and State of Vermont, have invented a new and useful Heating and Illuminating Apparatus; and do hereby declare the same to be fully described in the following specification, and represented in the accompanying drawings, of which—

Figure 1 is a front elevation, and Fig. 2 a vertical section, of it.

In such drawings, A denotes an ordinary lamp for burning kerosene, the burner b being provided with a globular glass chimney, B, having at top a neck, e, to enter and fit to an auxiliary metallic tapering chimney, C, extending up from the glass transparent chimney, as shown. The said metallic chimney goes up through a disk or shelf, D, supported by a series of rods, E E E, extending up from a clasp, F, which encompasses the burner at its base, and is provided with a clamp-screw to fasten it to the burner, a top view of the clasp being represented in Fig. 3. The auxiliary chimney goes up through a pitcher or pot, G, provided with a tube, g, extending up from and opening through its bottom, as shown in Fig. 4, which is a vertical section of the vessel. The tube g rises somewhat above the top of the vessel, and goes through its cover h, and fits thereto and to the auxiliary chimney. The vessel G is furnished with a handle, l, and a nose, i, whose opening or top is covered by a safety-cap, k, hinged to the main cover h.

Furthermore, the main cover h has a handle, m, for aiding in lifting the cover off the pot. The auxiliary metallic chimney will absorb heat and convey it to the contents of the pot, very much better than a glass chimney will, and besides it can be fitted to better advantage to the internal tube of the pot.

The above-described apparatus can be used for illumination or giving light to surrounding objects, as well as for heating a liquid when within the pot or vessel. The cap of the nose will serve as a safety-valve, in case of steam of too great pressure being produced in the pot.

The series of rods E E, arranged with the shelf D and the glass chimney B, in manner as shown, not only support the shelf better than a single post or rod, but act as supporters of and guards to the glass chimney. They aid in holding it in place. Furthermore, they, with the clasp F and the shelf D, serve to hold the auxiliary chimney in connection with the glass chimney, the auxiliary chimney being provided, as shown in the drawings, with a flange on which the shelf rests.

I claim—

The clasp F, the series of rods E E E E, the shelf D, the main and auxiliary chimneys B C, and the burner b, arranged and combined substantially as shown and described.

LAURENT RUEL.
